(57) **CLAIM**

The ornamental design for an integrated air compressor and winch, as shown and described.

DESCRIPTION

FIG. 1 is a front perspective view of an integrated air compressor and winch;

FIG. 2 is a front planar view thereof;

FIG. 3 is a back view thereof;

FIG. 4 is a top view thereof;

FIG. 5 is a bottom view thereof;

FIG. 6 is a right side view thereof; and,

FIG. 7 is a left side view thereof.

The phantom lines in FIGS. 1-7 are for illustrative purposes only and do not form part of the claimed invention.
